(57) **CLAIM**

The ornamental design for an interference bone screw, as shown and described.

DESCRIPTION

FIG. 1 is a front perspective view of an interference bone screw according to the present invention.

FIG. 2 is a front view of the interference bone screw of FIG. 1.

FIG. 3 is a rear view of the interference bone screw of FIG. 1.

FIG. 4 is a left side view of the interference bone screw of FIG. 1.

FIG. 5 is a right side view of the interference bone screw of FIG. 1.

FIG. 6 is a top view of the interference bone screw of FIG. 1; and,

FIG. 7 is a bottom view of the interference bone screw of FIG. 1.

The broken lines shown in FIGS. 1-7 illustrate portions of the interference bone screw that form no part of the claimed design.

1 Claim, 7 Drawing Sheets
